John Rogers

DES. 2195

John Rogers, of New York, N.Y.

Letter Patent No. 2195-Dated Oct. 10, 1865.

Design for a Group of Statuary.

The schedule referred to in these letters Patent and making part of the same.

to all whom it may concern:

Be it known that I, John Rogers, of the City and County of New York, and State of New York, have invented or produced a new and original design for a group of statuary, and I do hereby declare that the following is a full and exact description of the same. The group consists of three figures and is called the Bushwhacker and his wife appeal for peace. It represents the Bushwhacker holding his child in his right arm, while his wife, standing on the same side, looks up imploringly in his face, and attempts to draw his gun away from him - all of which are clearly seen in the accompanying drawings; and what I claim as my invention or production and desire to secure by letters Patent is the design for a group of figures as shown and described.
